ADJUSTABLE NECKBAND FOR COLLARS
AND SHIRTS

Ralph Edward Franklin, Minneapolis, Minn.

Application August 25, 1944, Serial No. 551,093

4 Claims. (Cl. 2—127).

This invention relates to circumferentially adjustable neckbands and collars for shirts.

It is a fact that regardless of the extent to which a collar or shirt is pre-shrunk, a certain amount of shrinking takes place after repeated laundering. Furthermore, the circumference of the neck of the average person varies slightly throughout the years and under different temperature and physical conditions.

It is an object of my invention to provide a simple and inexpensive structure which may be very readily embodied in attached or detachable shirt collars and through the use of which an adjustment in circumference of the neckband varying from one-eighth to one-half of an inch may be made at the election of the wearer.

More specifically it is an object to provide the neckband of an attached or detachable collar with a narrow straight reinforced zone extending transversely of the circumference thereof, which may be slit to increase the circumference of the collar.

A still further object is to provide an adjustable collar of the class described wherein provision for circumferential adjustment may be made without changing the over-lap of the free ends of the neckband and which may be conveniently and commercially applied to the manufacture of both collar attached shirts and shirt collars or neckbands with little additional cost and through the use of conventional machinery now employed in the manufacture of shirts.

These and other objects and advantages of my invention will be more apparent from the following description made in connection with the accompanying drawing, wherein like character references refer to the same parts throughout the several views and in which—

Fig. 1 is a front perspective view showing an embodiment of my invention applied to an attached folded collar of a shirt with one of my adjusting elements slit for increasing the circumference of the collar;

Fig. 2 is a vertical section taken through the shirt shown in Fig. 1 and looking forwardly toward the juncture of the free ends of the neckband, and;

Fig. 3 is a fragmentary vertical cross section taken on the line 3—3 of Fig. 1.

As shown in the drawing, my invention is applied to a conventional type of soft shirt with attached folded collar C having the usual double ply collar proper 4 attached to the double ply neckband 5 in conventional manner by a row of stitching 6 adjacent the upper edge of the neck-

band. The shirt proper is divided at the front in the usual manner along the line aligned with the ends of the collar band 5 and the free ends of the collar band are provided with the usual fastener means such as a button hole and button.

I provide in conjunction with the shirt collar heretofore described, a series of separable adjustment elements formed in the neckband 5 and extending transversely to the circumference thereof. Each of these elements comprises a reinforced substantially straight zone Z constituting a very narrow substantially vertical portion or strip of the integral fabric or plies constituting the collar band with a reinforcement surrounding said very narrow portion or zone and extending through the entire thickness of the collar band.

While other reinforcing medias may be successfully utilized, I prefer to form in a plurality of circumferentially spaced portions of the neckband, 20 an elongated complete button hole stitching S defining said separable very narrow area or zone Z and entirely surrounding the same. Button hole stitching is particularly adaptable for reinforcing the separable zone since it may be carried out quickly and at low cost, with standard machinery available to shirt and collar manufacturers. I prefer to provide at least one of said separable adjustment elements at the central rear of the neck with two or more disposed forwardly of the 25 rear adjustment element. I find that if two additional separable adjustment elements are utilized, the most convenient and effective positioning of the same is as shown in Fig. 2, spaced equidistant at the sides and front of the neck band, a few inches from the button hole for connecting the free ends of the band.

It is to be understood that the separable adjustment elements are not applied or extended through the collar proper 4 but in the manufacture of the shirt, are produced in the neckband 5 only with a reinforcing stitch or other reinforcing media extending through the full thickness (whether single or multiple) of the band. The material of the neckband is of course, left unsevered as clearly shown in Fig. 2 with the reinforcing media S defining a narrow area or zone Z which may be subsequently slit by the wearer for enlarging the circumference of the collar. In 30 Fig. 1 the adjustment element has been severed and is shown in separated condition giving an adjustment to the circumference of the neckband of approximately one-eighth of an inch in a full size collar. Further adjustment may be made in the same collar band severing one or

both of the unseparated adjustment elements shown in Fig. 2.

If, after severing one of the adjustment elements to increase the circumference of the collar, it becomes desirable to shorten the circumference, the slit, narrow zone may be stitched together very easily to cause the collar to resume its original circumference.

With my structure, it will be seen that when the narrow strip area or zone is severed, the fabric of the neckband cannot fray, tear or rip since it is reinforced and finished by the reinforcement or stitching S.

It will of course, be understood that any instrument such as a knife, shears or scalpel may be readily utilized to sever the zone Z longitudinally from one end of the button hole stitching or other reinforcing media.

It will be readily seen that my invention is as readily applicable to detachable collars or to the collar neckbands of conventional shirts to which detachable collars are applied.

It will, of course, be understood that various changes may be made in the form, details, arrangement and proportions of the parts without departing from the scope of my invention.

What is claimed is:

1. An adjustable neck band for shirts and collars having the usual free ends and having means for securing said ends together in a predetermined position, comprising at least one substantially straight, separable, very narrow area extending transversely of the circumference of the

band and defined and reinforced by a reinforcing element which binds the fabric of the band to prevent subsequent ripping or fraying thereof when said area is slit.

5. 2. In an adjustable neck band for shirts and collars having the usual free ends and having means for securing said ends together, severable adjustment means for said band comprising a plurality of circumferentially spaced reinforcing elements each defining a very narrow severable strip of the material itself of said collar band and extending therethrough, said strip extending transversely to the circumference of said band and said reinforcing element having reinforcement means disposed at least, along both elongated sides of said narrow strip to prevent subsequent ripping or fraying of the collar band material when said strip is severed for adjustment.

10 3. The structure set forth in claim 2 wherein said reinforcing element is endless and surrounds the entire severable strip.

15 4. In an adjustable neck band for shirts and collars having the usual free ends and having means for securing said ends together, a narrow elongated button hole stitch formed throughout the fabric in said band and extending transversely to the circumference thereof and defining a very narrow transverse area of said fabric which may be slit for increasing the circumference of said band, said stitch preventing subsequent ripping or fraying of said fabric when said area is severed.

RALPH EDWARD FRANKLIN.
